UNITED STATES PATENT OFFICE

115,631

DESIGN FOR A SELF-PHOTOGRAPHING APPARATUS

William W. Rice, Chicago, Ill.

Application February 23, 1939, Serial No. 83,160

Term of patent 3½ years

To all whom it may concern:

Be it known that I, William W. Rice, a citizen of the United States and a resident of Chicago, in the county of Cook and State of Illinois, have invented a new, original, and ornamental Design for a Self-Photographing Apparatus, of which the following is a specification, reference being had to the accompanying drawing, forming a part thereof, and in which:

Fig. 1 is a perspective view of a self-photo-

graphing apparatus showing my new design and as viewed when looking toward the entrance thereof; and

Fig. 2 is a top plan view of the self-photographing apparatus, with entrance at the left, showing my new design.

I claim:

The ornamental design for a self-photographing apparatus, as shown and described.

WILLIAM W. RICE.
